UNITED STATES PATENT OFFICE.

AUGUSTINE E. GREENE, OF HARTFORD, CONNECTICUT.

WORK-HOLDER.

1,024,256.

Specification of Letters Patent.

Patented Apr. 23, 1912.

Original application filed February 20, 1911, Serial No. 609,562. Divided and this application filed July 20, 1911. Serial No. 639,657.

To all whom it may concern:

Be it known that I, AUGUSTINE E. GREENE, a citizen of the United States of America, residing at Hartford, in the county of Hartford and State of Connecticut, have invented certain new and useful Improvements in Work-Holders, the same being a divisional part of an application filed by me in the United States Patent Office February 20, 1911, and serially numbered 609,562, of which the following is a specification.

My invention relates to improvements in devices for holding spherical objects while being ground, polished, or otherwise treated or dressed, and especially adapted for ball-making or -finishing machines, and resides in certain peculiar mechanical means for utilizing an elemental force to hold and release such objects, as hereinafter set forth.

With this work holder the member, at the end of which it is necessary to hold an object so that it can be subjected to the action of an abrading member, has imparted to its axis of rotation a varying conical rotation, varying because the angle of inclination of such axis to the non-oscillatory axis about which said first-mentioned axis revolves is changeable. This is a valuable and important feature for the obvious reason that provision is thus made for abrading the object evenly and uniformly and producing a true sphere.

The object of my invention is, therefore, to provide a coacting and highly efficient work holder which is capable of holding an object and imparting a rapid gyratory motion thereto while the same is being ground, polished, or otherwise treated or dressed, and this without impairing, injuring, or changing the properties or inherent characteristics or qualities of the material from which such object is made, and regardless of the character of the object.

Other objects will appear in the course of the following description.

I attain these objects by the mechanism illustrated in the accompanying drawings, in which—

Figure 1 is a top plan of so much of a ball-making or -finishing machine as is requisite to show the application of a practical form of my invention; Fig. 2, an enlarged side elevation of one of the magnetic

chucks and associated parts, a portion of the 55 drum which carries these members appearing in section; Fig. 3, a similar view to the preceding, as said chuck and associated parts appear from above; Fig. 4, a vertical section taken on lines 4—4, looking in the 60 direction of the associated arrow, in Fig. 2; Fig. 5, a front elevation of the part of the machine shown in the first view; Fig. 6, a diagram illustrative of the action of the 65 work holder; Fig. 7, an enlarged top plan of the clutch which controls the drum; Fig. 8, an enlarged face view of said clutch, looking from the left; Fig. 9, a right-hand elevation of said machine, without the supporting legs; Fig. 10, a vertical section taken 70 on lines 10—10, looking in the direction of the associated arrow, in Fig. 5; Fig. 11, a front elevation of the machine head equipped with pneumatic work-holding 75 mechanism, instead of electro-magnetic work-holding mechanism as in the first instance; Fig. 12, an enlarged inner face view of the stationary air- or suction-chamber case; Fig. 13, an enlarged face view of the revolute ring which fits into said case and 80 has the chuck spindles connected therewith, as viewed from the left, one pair of the spindle-holding plates being omitted; Fig. 14, an enlarged detail, in partial section, showing most of the principal parts of the 85 pneumatic head, intermediate portions of the spindles being broken out, and the section through the air-chamber case being taken on lines 14—14, looking in the direction of the associated arrow, in Fig. 12, and, 90 Fig. 15, an enlarged fragmentary detail, in section, of parts of the so-called suction mechanism.

Similar figures refer to similar parts throughout the several views. 95

Before proceeding to describe my invention and its application in detail, I wish to state that, with this work holder, an object which it is adapted to handle is brought under the influence of an attracting or holding elemental force, such as electro-magnetism or so-called suction created by a partial vacuum produced by exhausting the air from a container, and while in the power or under the dominance of this force said 100 chuck is rotated about one axis and coincidentally oscillated upon another axis which is at right-angles to the first, the point of

intersection between the two axes being fixed or permanent and with which the true center of the finished object coincides. A finished object, a ball in this case, is represented at 5 1, in Figs. 3 and 6, and the point just mentioned as being that upon which the ball turns in two directions at right-angles to each other is the exact center of said ball 1. Thus it is clear that the motion of the ball 10 may be described as a spiral, conical rotation of an axis of rotation, in short, as gyroscopic. Because of this gyroscopic motion imparted to the ball by the work holder, one-half or something more than one-half 15 of the superficial area of the ball can be presented to a rotary member having an axis which if continued would coincide with the principal or main axis of the ball or of said holder, in such a manner that the ball receives uniform treatment from said rotary member, which would not be the case if there were no gyroscopic motion to cause all 20 parts of the surface presented to receive the same amount of treatment from the aforesaid member, because then those portions of such surface that were at and nearest to the axial center of the rotary member would be subjected to less frictional energy, since the speed of the rotary member is less the nearer 25 its axial center is approached, than those portions of said surface that were farthest from such center, where the speed of said member is greatest. Thus it is plain that the work holder so manipulates the ball as to 30 equalize the action of the rotary member thereon.

Not only is the fixed point or center of motion of the ball, and about which said ball is simultaneously revolved and oscillated by the work holder, represented by the 35 center of the ball 1, in Fig. 6, but there are also represented in said view the principal or main axis, at 2, and five possible positions of the axis of rotation, at 3, which 40 will assist in understanding the operation of the work holder. The axis of rotation is fixed at the ball end of the work holder, where said axis may be said to fulcrum, but it is or may be flexible or jointed so that 45 the other end can be moved longitudinally on the axis 2, as when actuated by a cam, and the lines 5 indicate such complementary parts in the aforesaid five positions of such axis. In this way the axis of rotation becomes an oscillatory axis of rotation around 50 the principal or main axis.

The parts of the machine herein shown, and with which either the electro-magnetic or the suction work holders may be employed, are briefly described as follows: A portion of a frame is represented at 6, which frame has head bearings 7-7 and caps 8-8 for horizontal, rotary, ball-operating drum 9. At 11 appears a supporting stand 65 for a horizontal, abrader-operating carriage

12 which is reciprocable in a direction longitudinally of the machine, the operating mechanism therefor being omitted. An upstanding support 13 and a friction member 15 thereon also appear. Journaled in the frame 6, below but in the rear of the vertical plane of the axis of the drum 9, is a shaft 16. Secured to the outer end of the shaft 16 is a driving pulley 17 which is driven by a belt 18 from a main or counter-shaft (not shown). Secured also to the shaft 16, inside of the pulley 17, is a gear 19 that meshes with a small gear 20 loose on a stud 21 projecting from the outer end of the frame head and having its axis in line with the axis of the drum 9. Secured on the inner end of the shaft 16 is a gear 22. Journaled in the longitudinal center of the frame 6 is a shaft 23 which is driven from the shaft 16 through the medium of the gear 22 and a gear 24 secured to said shaft 23 and meshing with said first-mentioned gear. A short shaft 25 is journaled in the frame head and this shaft has a gear 26 secured on its outer protruding terminal to mesh with 25 a large gear 27 on the outer end of the drum 9.

To drive the drum intermittently from the shaft 23, through the medium of the gears 27 and 26 and the shaft 25, a clutch is provided, which consists of a cam-like clutch proper 28 and a disk 29 secured to the adjacent ends of said shafts, respectively. These shafts are out of alinement, and the clutch 28 has a peripheral tooth 30 while the disk 29 has two oppositely-disposed lugs 31 which extend to the left into the path of said tooth. Referring more particularly to Fig. 8, it will be seen how, as the clutch 28 revolves in the direction of the arrow there shown, the tooth 30 contacts with one of the lugs 31 and wedges its cam edge against the other lug 31 and so carries the disk 29 around until said disk makes one-half of a revolution, when, owing to the eccentricity 100 of the axes of said clutch and disk, said clutch clears said lugs and makes the other half of its revolution without said disk. Thus at every revolution of the shaft 23 the shaft 25 makes a half revolution, and since 105 the gear 24 is only one-fourth the size of the gear 27, the drum 9 is caused to revolve one-fourth of the way around.

The ball-operating mechanism comprises 110 the drum 9 and the other parts and members operated thereby and closely associated therewith which will now be described in detail.

Revolubly mounted or journaled in the drum 9 and extending beyond both ends 115 thereof are four spindles 32. These spindles are arranged at equal distances from the longitudinal center of the drum and at equal distances from each other, and have secured on their outer ends pinions 33 which mesh 120

with the constantly revolving gear 20. Each spindle 32 is provided at its inner terminal with a yoke 34, and slidably mounted on such spindle is a sleeve 35 formed into a cam 36 at the end adjacent to the drum 9. A spring 37 encircling each spindle 32 between its yoke 34 and a washer 38 which bears against projecting parts of the sleeve 35 on said spindle, and retains said sleeve 10 with its cam 36 against an abutment in the form of a roll 39 which is in the path of said cam. There is a roll 39 for each cam 36, and such roll is mounted on a stud 40 carried by a supporting bracket 41 that is 15 rigidly attached to the drum in proper relation to the adjacent cam. Pivottally attached at 42—42 to each sleeve 35 is a yoke 43, and pivotally attached at 44 to the left-hand terminal of said yoke is a chuck 45. 20 Each chuck 45 has two arms 46, at the end opposite that which is pivoted to the supporting yoke 43 therefor, and these arms are pivoted at 47—47 to the free terminals of the associated yoke 34, inside of the arms 25 or branches of the same. If the pivots 47 are of insufficient strength and rigidity to prevent the connected chuck, yoke and cam-sleeve from turning on the supporting spindle, said sleeve can be keyed to said spindle 30 in the usual manner, or any other suitable additional means may be employed to that end. Each chuck 45 has a core 48 which projects from the barrel or spool of such chuck between the arms 46 and constitutes 35 the actual holder for the balls. When the chuck is of the electro-magnetic type, the core or holder proper 48 is made of soft iron so that only the minimum amount of residual magnetism will be retained by it. 40 The exposed end of this core or holder is hollowed or cupped more or less to fit the balls and form a good and sufficient contact or connection therewith.

The roll 39 in each case is so situated that 45 the contacting cam-sleeve 35 can never slide on its spindle 32 far enough toward the drum 9 to allow the axis of the associated chuck 45 to coincide with the axis of said spindle, and, since said chuck swings at one 50 end on an axis, represented by the pivots 47, the angle of inclination of the chuck axis changes as the parts revolve with said spindle, because said sleeve is then reciprocated by reason of the contact between its 55 cam 36 and said roll, and through the medium of the connecting yoke 43. Thus the point of intersection between the spindle axis, which is the principal or main axis corresponding with the line 2 in Fig. 6, and 60 the secondary axis or the axis upon which the chuck oscillates, represented by the pivots 47, becomes the point about which the revolution and the oscillation of the chuck take place, and is the center of the perfect ball, it being understood that the distance 65

from such point to the center of the holder 48 is equal to one-half the diameter of such ball. The axis of the chuck is represented by the lines 3 and the connecting or longitudinal axis of the yoke 43 by the lines 5, in 70 Fig. 6, in five different possible positions given them by the cam acting against the roll and moving the adjacent end of said yoke along the spindle axis. By this means and in this manner a ball in the holder 75 receives the motion already very fully described.

To retain the ball firmly and securely in any holder 48, either electro-magnetism, or suction which is produced by a partial vacuum, is employed. I will here explain the means for applying the former, leaving the explanation of the means for utilizing the latter until later.

The drum 9 is provided with a commutator 49 for each chuck 45 when of the electro-magnetic type, and a brush 50 is provided for each commutator, such brush depending from an insulated bracket 51 mounted on the inner cap 8 and extending 85 to the right over the commutators. Screws 52 are provided for the adjustment of the brushes 50, and binding-posts 53, as usual. Wires 54 lead from the binding-posts 53 to a suitable source of electrical energy, indicated at 55, in Fig. 1, and a wire 56 leads from such source to a non-insulated binding-post 57 on the outer cap 8. Each commutator is connected, in the customary manner, by a wire 58 with a binding-post 59 set 90 in an insulated bracket 60 attached to the drum adjacent to one of the spindles 32, and a short wire 61 connects such binding-post with a brush 62. Each brush 62 is adjustably held in one of the brackets 60 by a 100 screw 63.

Secured to each spindle 32, with a ring 64 of insulating material between, is a contact ring 65 against which one of the brushes 62 bears. A wire 66 leads from each contact 110 ring 65 to a binding-post 67 at the inner end of one of the arms or branches of the yoke 34 which is at the inner terminal of the spindle 32 upon which such ring is mounted, said wire passing from said ring through 115 radial openings in the associated insulating ring 64 and spindle to a central longitudinal passageway 68 in said spindle, as shown in Fig. 4, thence through such passageway to said yoke, out through a suitable opening 120 therein, and along the outside of the yoke arm which supports said binding-post to the latter, as best shown in Fig. 3, the aforesaid opening in the yoke being represented by dotted lines at 69. A short wire 70 connects the binding-post 67 with a binding-post 71 on the chuck 45 in this combination, and the circuit to the frame is completed through a short wire 72 which connects two 125 binding-posts 73 and 74 also on said chuck, 130

but the binding-post 74 being non-insulated. The binding-posts 71 and 73 are the terminals of the electro-magnet which forms a part of each chuck 45 in this instance. 5 Thus the circuit from the source of energy at 55 to any chuck 45 and back to such source is formed by the proper wire 54, brush 50 and commutator 49, and the wires 58 and 61, brush 62, ring 65, and the wires 66, 70 and 72 in the combination, the frame 10 of the machine, and the wire 56.

The arrangement of the commutators 49 and the timing of the drum 9 are such that each chuck 45 or its holder 48 is magnetized and demagnetized four times at every revolution of said drum, but all of said holders are not magnetized and demagnetized together. When any holder 48 is magnetized it attracts to itself and holds 20 securely any ball that is a good subject for magnetic attraction when brought into the field of such attraction emanating from such holder, and releases said ball upon being demagnetized.

25 Of the abrader-operating mechanism with which this machine is provided, only the front-end portion of the carriage 12 and the front-end portions of two revoluble spindles 75, together with two abraders 76 30 attached to said spindles, are shown. The abraders 76 are cupped in the centers of their working faces to receive the balls, in much the same manner as are the holders 48, and when said abraders are in operative 35 position the centers of the cupped portions thereof coincide or approximately coincide with the circular path at the left-hand ends of the horizontal diameters of the finished balls carried by the chucks 45. In other 40 words, the point of intersection between the oscillatory axis of rotation and the main or principal axis around which such oscillatory axis revolves, of any chuck in grinding position is the same distance from the center 45 of the concavity in a juxtaposed abrader, that is, of an abrader 76 the axis of which if continued would coincide with said main or principal axis, as it is from the center of the concavity in the holder 48 of said 50 chuck.

55 Of the ball-feeding mechanism with which the machine is provided, there are shown only a trough or raceway 77, the upper part of a support 78 for such raceway, and a brace 79 for such support. From its front end, which is attached to the support 78, the raceway 77 curves rearwardly and slants downwardly to open at its back end toward the orbit of the holders 60 48 and at a point which is below the advanced position of the working face of the forward abrader 76. This raceway receives the balls and delivers them to the holders.

65 The operation of the ball-holding mechanism as a whole is as follows, it being as-

sumed that the pulley 17 and the shaft 16 are revolving, and that the revoluble members are rotating, either constantly or intermittently, as the case may be, in the directions indicated by the arrows associated therewith. The gear 19, on the shaft 16 with the pulley 17, through the medium of the intermediate gear 20 and the pinions 33, causes the four spindles 32 to revolve constantly; and the gear 22, also on said shaft and through the medium of the gear 24, causes the shaft 23 also to revolve constantly. When the first ball 1 arrives at the discharge end of the raceway 77, said ball comes into contact with an energized holder 48 that is in position to receive it and to pick it from said raceway and securely hold it, the circuit to and through the chuck 45, of which said holder forms a part, being now closed by reason of the fact that the commutator 49 which belongs in said circuit has one of its electric contact segments in contact with its brush 50. Although the spindle 32 with which the aforesaid chuck is connected is revolving the circuit is not interfered with because of the presence of one of the contact rings 65 on such spindle, and the connection afforded by the brush 62 which bears on said ring. While thus held by the energizing chuck 45 in question, which for convenience will be called the first chuck, the ball is carried thereby from the receiving position to the first abrading position in line with the forward abrader 76, and is there acted on by said abrader. The first chuck with the ball is moved into the new position by reason of the fact that the clutch 28 on the constantly revolving shaft 23 engages the lugs 31 and imparts to the disk 29 and the shaft 25 one-half of a revolution, and that said shaft 25 in turn with its gear 26 imparts one-fourth of a revolution to the gear 27 and the drum 9 which carries said chuck; and said chuck with the ball is left in such position because by the time or at the time it arrives there, said clutch clears said lugs and the movement of said drum ceases. The ball is rotated and oscillated in the peculiar manner previously set forth, and said ball is subjected on one side to the action of the forward abrader until the latter is retracted, when the clutch operates to give the drum another quarter turn. Meanwhile the second chuck has picked the second ball from the raceway 77 at the receiving position. Upon the second quarter of the revolution of the drum 9 the first ball is caused to traverse the friction member 15, and just after said ball reaches said member the first chuck is demagnetized, so as to enable the ball to roll in its holder or to be rolled therein by frictional contact with said member, and just before said ball leaves said member said chuck is magnetized again. 130

- The first ball, thus turned half way around so as to present the undressed side to the rear abrader 76, is next left at the second abrading position, when for the second time 5 the clutch 28 frees the disk 29 and the abraders when advanced operate on two balls, the rear abrader operating on the first ball attached to the first chuck and the forward abrader operating on the second. 10 ball attached to the second chuck. Thus one side of each ball is dressed by the forward abrader, and the other side by the rear abrader. The results produced by the third quarter of the revolution of the drum are 15 that the first ball is dropped from its now demagnetized chuck, the second ball is carried to the second abrading position and turned half way around on the way, and the third ball, which the third chuck has 20 already picked, is brought into the first abrading position. With the completion of the revolution of the drum, during the last quarter of which the second ball is dropped, the third ball is carried to the second abrading position and the fourth ball held by 25 the fourth chuck to the first abrading position, and the first chuck is again magnetized so that it can and does pick the fifth ball, one cycle of the machine is complete, 30 provided such cycle start with the picking of the first ball by the first chuck, in accordance with the foregoing description. During this cycle the clutch operates at four regular intervals, the abraders are advanced and retracted four times, and each 35 chuck is demagnetized twice, once when it passes the friction member 15, and once again when it drops the ball after the second abrading. 40 Taking up, finally, the vacuum or suction devices illustrated on the last two sheets of the drawings, it will be seen that means for handling the balls with air take the place of electromagnetic means for that purpose, and that the drum 9 without the commutators, the driving mechanism for such 45 drum, the spindles 32 and their yokes, the spring-pressed cam-sleeves 35 and the rolls 39 therefor, and the holders 48, of the other 50 construction, are all retained and do not greatly differ, whenever they differ at all, from corresponding parts and members in the other construction. 55 Pointing out in detail the differences alluded to in the preceding paragraph, attention is called to the substitution of a shaft 80 for the stud 21, the narrowing of the intermediate gear 20 thereon, and the presence of an additional intermediate 60 gear 81 secured to said shaft, with said gear 20, to mesh with the gear 19, Fig. 11; and then to the flange or head 82 at the outer end of each spindle 32, a rear passage 83, which, unlike the wire passageway 68 in the 65 first instance, extends the entire length of said spindle, branches at the yoke 34 which forms a part of the spindle, and extends to the openings in the arms of such yoke at the ends for the pivots 47, and air passages 84-84 in said pivots. Each pair of pivots 70 47 is here prevented from turning by means of two bolts 85 tapped into the free ends of the supporting yoke 34 into engagement with said pivots. Mounted on the inner terminals of each pair of these pivots, 75 in practically the same way as the electromagnetic chucks are mounted, is an air or vacuum chuck 86 pivotally connected at 44 with two arms 87, these members being arranged and adapted to operate mechanically in the same way as do the chucks 45 and the yokes 43. Like the chucks 45, the chucks 86 have ball holders 48, and there is a branching air passage 88 in the head of each of said chucks 86, which passage leads 80 from the center of the chuck holder to the openings in the chuck arms for the pivots 47. The passage 84 in each pivot 47 connects with the branch of the passage 83 which is in the supporting yoke arm for 85 such pivot, and also connects with the branch of the passage 88 which is in the arm 46 that is mounted on said pivot, so that there is a clear air passageway from the left-hand open end of the holder of 90 each air chuck, through said chuck and by way of the connecting pivots to and through the supporting yoke 34 and the entire length of the supporting spindle 32. At the junction of the passages 83 and 84 95 such passages must be large enough, of course, to enable the air chucks to rock, when the mechanism is in operation, without closing the same. 100
- The axis of each spindle 32, in the suction or vacuum mechanism, corresponds with the line 2, in Fig. 6, and the chuck 86 and arms 87 assume the same positions while revolving as those indicated by the lines 3 and 5, in said view. 105
- Suitably supported by a bracket 89 from the outer cap 8 is a case 90 having an annular air or suction chamber 91 therein, Figs. 11, 12, 14 and 15. The case 90 is suspended between the gears 20 and 81, and the shaft 80 extends through the center thereof. The inner wall of the case 90 is provided exteriorly with two annular flanges 92 and 93, the former being smaller than the latter. The flange 93 is an extension laterally of the periphery of the case 90. There is thus formed a circular channel 94. The chamber 91 opens into the channel 94 through two arcuate slots 95 and 96 and a round opening 97 in the wall between. A pipe 98 leads from the chamber 91, at any convenient point, to a pump (not shown) for exhausting the air from said chamber. Two radial ports 99 and 100 are made in the flange 93 to establish commu- 110
- 115
- 120
- 125
- 130

nication with the channel 94 from the outside. A coupling ring 101 fits and is adapted to revolve freely in the channel 94, being secured in place on the open side of said channel by means of outer and inner rings 102 and 103 fixed to the edges of the flanges 93 and 92, respectively. Thus said flanges form a journal for the coupling ring.

10 Equidistant from each other in the coupling ring 101 are four recesses 104 formed in the left-hand face of said ring, and these recessed portions are further recessed, in the center of each at 105, to provide journals for the spindle-heads 82, and slotted at 106, the slots being concentric with the slots 95 and 96 and the hole 97, and opening through the plain right-hand side of said ring and through the recessed side thereof. 15 Each head 82 is held in its recess 106 by means of a pair of abutting segmental plates 107 fastened in the recess 104 provided for their reception. The plates 107 have openings 108 in their abutting edges of a size to accommodate the necks of the spindles 32 or the portions of such spindles that are between the heads 82 and the parts of said spindles upon which the pinions 33 are mounted, but not large enough for the 20 passage of said heads. There are four radial ports 109 in the coupling ring, each of which opens at its inner end into one of the slots 106 at one end of the same, and at the other end through the periphery of said ring. The ports 99, 100 and 109 are all in the same vertical plane in order to enable any one of the latter to be brought into alinement with either of the two former.

Clearly from the above the drum 9 in its 40 rotation carries with it the spindles 32, as before, and rotates the coupling ring 101 which is securely attached to the outer terminals of said spindles by the plates 107, such ring traveling around in the channel 45 94, consequently each slot 106 is brought into open communication with the slots 95 and 96 and with the opening 97, one after another, and each port 109 is brought into alinement with the ports 99 and 100, one 50 after the other.

Assuming that there is a partial vacuum in the chamber 91, and that the machine is running and the ring 101 has been turned so as to locate one of the slots 106 in open 55 communication with the slot 96, air is being sucked through into said chamber from the holder 48 which is in communication through the connecting passages with said slot 106, or there is a suction at said holder, 60 and such suction has sufficient force to hold a ball while being abraded. This suction commences as soon as the aforesaid slot 106 passes into open relation with the slot 96, and continues while a ball is picked at the 65 receiving position, taken to the first abrad-

ing position, abraded on one side and passed on to the friction member 15, said drum and ring having meanwhile made two quarter turns and carried said slot 106 into open relation with the slot 95, such relation being 70 established before said slot 106 leaves said slot 96, and finally taken the slot 106 beyond said slot 95, and brought the communicating port 109 into line with the port 99. The suction is thus cut off and air admitted 75 at the alining ports or through the alining ports to break the vacuum, and the ball freed in this manner is rolled over or given a half revolution as it is carried past the member 15 and before the slot 106, which is 80 new being followed in its course, arrives at the opening 97. When said slot does arrive at said opening, which is just as the ball is about to leave the member 15, the vacuum is reestablished and said ball is advanced to 85 the second abrading position, abraded, and carried on to discharging position before said slot leaves said opening. Very soon after communication with the chamber 91 is 90 cut off a second time, communication is had with the port 100, as shown in Fig. 15, the vacuum is again broken, and the ball in consequence permitted to drop from its now powerless holder. By the time said holder is in position to pick another ball, however, 95 its associated slot 106 will have once more come into open relationship with the slot 96. The operation of the air or vacuum controlling parts and members is alike in the case of each vacuum chuck, the same being 100 energized twice and twice rendered powerless by the breaking of the vacuum at each complete revolution of the drum and coupling ring; and the constant and intermittent rotary and the constant oscillatory motions of the parts, including the drum, spindles and chucks, are the same as has been fully explained in connection with the electro-magnetic chucks and associated parts.

The vacuum chucks 86, as they appear in Fig. 14, while relatively in correct positions, are not as they would be if in the machine and occupying corresponding positions, because the case 90 is sectioned on lines 14—14, Fig. 12.

115 The top and middle chucks 86 are energized and holding balls, and the bottom chuck 86 is "dead," in Fig. 14. Were these three chucks in the same relative positions in the machine and in operation, the uppermost chuck would be without energy and traversing the friction member 15 with a loose ball, the lowermost chuck would be energized and about to pick a ball, and the middle chuck would be without energy and 120 would have just dropped a ball, while the fourth chuck, which does not appear in this view, would be energized and in the act of carrying a ball just taken at the receiving position to the first abrading position. The 125 130

front end of the drum is represented in Fig. 14 by dot-and-dash lines.

The suction member, including the vacuum chucks, is designed to handle balls of 5 wood, ivory, and other substances and materials which, unlike balls of steel for example, cannot be handled successfully or at all by the electro-magnetic chucks.

Obviously my invention is susceptible to 10 considerable modification and change without departure from the spirit thereof, hence I do not desire or intend to limit myself to the construction set out herein.

What I claim as my invention, and desire 15 to secure by Letters Patent, is—

1. A work-holder, for spherical objects, comprising rotary object-holding means, and means to impart a conical rotation to the axis of rotation of said first-mentioned 20 means.

2. A work-holder, for spherical objects, comprising rotary object-holding means, and means to impart a changing conical ro-

tation to the axis of rotation of said first-mentioned means.

25

3. A work-holder, for spherical objects, comprising object-holding means, means to rotate said object-holding means on a principal or main axis, and means to impart an oscillatory rotation around said principal 30 or main axis to said object-holding means.

4. In a machine for acting on spherical objects, an intermittently rotating member, a chuck carried by said member, and means to energize said chuck automatically at pre- 35 determined intervals.

5. In a machine for acting on spherical objects, an intermittently rotating member, a chuck carried by said member, means to energize said chuck automatically at pre- 40 determined intervals, and means to impart a gyratory motion to said chuck.

AUGUSTINE E. GREENE.
